UNITED STATES PATENT OFFICE.

MILTON F. BABCOCK, OF BUFFALO, NEW YORK.

AIRPLANE.

1,427,086.

Specification of Letters Patent. Patented Aug. 29, 1922.

Application filed July 7, 1919. Serial No. 309,030.

To all whom it may concern:

Be it known that I, MILTON F. BABCOCK, a citizen of the Dominion of Canada, residing at Buffalo, in the county of Erie and 5 State of New York, have invented certain new and useful Improvements in Airplanes, of which the following is a specification.

This invention relates to airplanes, and an object of the invention is to provide a 10 construction for maintaining lateral stability of an airplane, and also for increasing the speed range.

The underlying principle of this invention is that the deep cambered aerofoil or wing 15 surface gives a greater lift per square foot of area than does a flat cambered aerofoil; therefore for lateral stability, the variable cambered sections of the aerofoil on one side is deepened in curvature while on the opposite side it is flattened proportionately, thereby giving a greater lift to one side of the airplane than upon the other.

For increasing the speed range; the camber of the variable cambered sections on 25 both sides of the fuselage is increased, thereby allowing the airplane to land or get away at the slow speed that is typical of deep cambered wing surfaces and which facilitates the ascensional efforts of the airplane. 30 Once the machine is in the air, the variable cambered sections are flattened to the normal wing curvature, thereby allowing the airplane to assume the high speed obtainable from flat cambered wings.

35 It is an object of this invention to provide variable cambered aerofoils or wings for airplanes, which will accomplish the above mentioned results, and to provide means for operating these variable cambered 40 sections which will permit the performance of both operations, namely the maintaining of the lateral stability of the airplane and the varying of the camber of the aerofoils at the same time, or independently of each 45 other, as desired.

Other objects of the invention are to provide a construction as specified wherein the aerofoil is not subjected to a helicoidal warp, but the curvature of the aerofoil is 50 changed uniformly from one lateral marginal portion through the entire length of the aerofoil to the other, or when the variable cambered wings are used for lateral stabilizing purposes, from one lateral marginal portion to the central axis of the aero- 55

foil and to provide an aerofoil structure wherein the front portion of the variable cambered wings is made up of one section from the main front spar of the wing to the leading edge and from the wing pit to the 60 end of the wing section laterally. This front portion works in conjunction with the marginal portion of the wing from the rear main spar to the trailing edge, which is likewise of one section, and from the wing pit 65 to the end of the section laterally. When the leading edge moves downward, the trailing edge also moves downward, thereby increasing the camber of the wing section and eliminating any strain upon the cross covering of the aerofoil as the latter is in no way expanded or contracted by the action of the 70 camber edges of the aerofoil.

Other objects of the invention will appear in the following detailed description, taken 75 in connection with the accompanying drawings, forming a part of this specification, and in which drawings:

Figure 1 is a side elevation of an airplane constructed in accordance with this invention.

Figure 2 is a top plan of the airplane.

Figure 3 is a vertical transverse section through an aerofoil of the variable camber construction.

Figure 4 is a fragmentary top plan of the aerofoil.

Figure 5 is a fragmentary end view of the operating and controlling mechanism for the cambered sections of the aerofoil.

Figure 6 is a section on the line 6-6 of Fig. 5.

Figure 7 is a diagrammatic view showing the method of changing or varying the camber of the aerofoils.

Referring more particularly to the drawings, where like characters indicate like and corresponding parts throughout the several views, the fuselage of the airplane is generically indicated by the letter A, and while the 100 particular aerofoil construction and the mechanism for operating the same is shown as applied to a two-seater pusher airplane, it is to be understood that the principle and construction of the aerofoils and their controlling mechanisms may be applied to airplanes of any approved type without departing from the spirit of this invention.

The drawings also illustrate a bi-plane, and in describing the invention, reference 110

will be had to only one of the planes or aerofoils, in that the construction of the multiple planes are identical.

The aerofoil 1, includes the central section 2 having the front and rear spars 3 and 4 which extend throughout the entire span of the aerofoil and are connected at spaced points by hollow ribs 5. The front spar 3 has the front portion 6 of the variable camber aerofoil hingedly connected thereto, as shown at 7, and this front portion extends from the leading edge to the main front spar 3 as clearly shown in Fig. 3 of the drawings. This front portion 6 works in conjunction with the marginal portion 8 which extends from the main rear spar 4 to the trailing edge of the aerofoil. These front and rear portions 6 and 8 extend throughout the entire span of the aerofoil, or 20 from the wing or aerofoil tips to the end of the wing section laterally as indicated at 9 in Fig. 2 of the drawings.

The strips 10 and 11 of the front and rear sections 6 and 8 respectively have arms attached thereto and projecting above and below the aerofoil 1. The arm 12 which is carried by the front portion 6, is connected by means of a guy wire 13 to the arm 14 which is carried by the strip 11 and this arm 14 extends downwardly from the under surface of the aerofoil while the arm 15, which projects downwardly from the under surface of the front portion 6 is connected to the arm 16 which projects upwardly from the rear portion 8 by a wire 17. These wires cross intermediate their ends, as clearly shown in Fig. 3 of the drawings, and they are provided for simultaneously operating the front and rear sections 6 and 8 to vary the camber 40 of the aerofoil. If it is desired, suitable guy or bracing wires 18 may extend from the outer ends of the arms to the free edges of the sections 6 and 8.

These sections 6 and 8 are operated for varying the camber of the wing by the operating structure generically indicated by the letter B. The operating structure includes the provision of a suitable supporting frame 20 which may be carried by the fuselage A at any point to be conveniently operated by the pilot of the airplane and this supporting frame 20 has a depending saddle 21 formed thereon which rotatably supports a stem or rod 22. The rod 22 is provided with threaded sections 23 and 24, the threads of which are oppositely disposed as clearly shown in Fig. 5 of the drawings. A hand wheel 25 is mounted upon the rod 22 for rotating the same and the rotation of this 60 rod will move the nuts 26 and 27 in opposite directions; that is upon rotation of the rod 22 in one direction the nuts 26 and 27 will be moved towards each other while upon rotation of the rod in opposite direction, they will be moved away from each

other. Pins 28 are carried by the nut 26, and corresponding pins 29 are carried by the nut 27. The pins 28 have pulleys 30 and 31 mounted thereon, while pulleys 32 and 33 are carried by the pins 29. A wire or cable 34 has one end connected to the arms 16 carried by the rear section 8 upon one side of the longitudinal center of the airplane and this cable passes over a suitable guiding pulley 35, which is carried by the aerofoil 1 75 and to and about a guide pulley 36, passing from the inner side of this pulley to the outer side and about a guide pulley 37 which latter pulleys are carried by the frame 20. From the guide pulley 37, the cable 34 passes 80 to and about the pulleys 30 from this pulley to and about the pulley 32 from which it passes, back beneath the guide pulley 30 to and about guide pulleys 38 and 39 which are carried by the frame 20 and from thence to 85 and about a guide pulley 40 carried by the aerofoil 1 upon the opposite side of the longitudinal center of the airplane from the aerofoil which carries the guide pulley 30. The cable 34 is finally connected to the arms 90 16 of the aerofoil which portion thereof carries the pulley 40 as clearly shown in the diagrammatic Fig. 7.

A second cable 41 is provided in the controlling mechanism which has one end connected to the arm 14 of the aerofoil 1 upon one side of the longitudinal center of the airplane and it passes, from its point of connection with the arm 14 to and about a guide pulley 42 carried by the aerofoil, downwardly to the pulley 43 which is carried by the frame 20 and from this pulley upwardly about a second guide pulley 44. After leaving the guide pulley 44, the cable 41 passes about the guide pulley 33, carried by the pin 105 29 of the nut 27, from there about a guide pulley 45 which is spaced outwardly from the guide pulley 33, as clearly shown in Figs. 5 and 7 of the drawings. From the guide pulley 45, the cable 41 extends to and 110 is coiled about a drum 46. The drum 46 is carried by a shaft 47 which is in turn rotatably supported by the supporting frame 20. The cable 41 passes off the drum 46 to and about a guide pulley 48 carried by 115 the frame 20 oppositely of the shaft 47 from the pulley 45. From the pulley 48 the cable passes to and about the pulley 31, pulleys 49 and 50 from which latter pulley it extends to the aerofoil 1 upon the opposite side 120 of the longitudinal center of the airplane from the aerofoil section which carries the pulley 42 and this cable is finally connected to the arm 14 of the rear section 8 of the last mentioned section of the aerofoil. The shaft 125 47 has a hand wheel 52 mounted thereon for manually rotating the shaft and by rotating the shaft 47, the cable 41 may be operated to vary the camber of the sections of the aerofoil upon each side of the longi- 130

tudinal center of the airplane, for maintaining the lateral stability of the airplane. It will be seen, by the diagrammatic Fig. 7 that when the drum 46 is rotated, it will increase the curvature of the wings or aerofoil section upon one side of the longitudinal center of the airplane and decrease the curvature of the section of the aerofoil upon the opposite side of the longitudinal center of the airplane, thereby increasing the dynamic lift upon one side of the airplane causing the same to right itself and maintain its lateral stability.

For varying the camber of the wings or aerofoils relative to the regulation of the speed of the airplane, the rod 22 is rotated, through the medium of the hand wheel 25. For instance, when the rod 22 is rotated for moving the nuts 26 and 27 towards each other, the length of the cable 34 between the guide pulleys 30 and 32 will be decreased, consequently increasing the lengths of the cable extending between these pulleys and the arms 16 allowing the arms 16 to move in the direction indicated by the arrows D shown in Fig. 7 of the drawings, and this movement will shorten the portions of the cable 41 between the pulleys 31 and 33 and the arms 14 of the aerofoil, moving the arms 14 in the direction oppositely to that indicated by the arrows D and consequently dipping the rear portion 8 of the aerofoil. Through the medium of the wires 13 the front section 6 will be simultaneously dipped and the camber of the aerofoil will be increased without variation of the angle of incident thereof. Upon the reversing of the direction of rotation of the rod 22, the above operation will be reversed, and the section 8 moves upwardly or straightens to decrease the curvature of the aerofoil; thus it will be seen that the curvature of the wing or aerofoil will be changed uniformly from one lateral marginal portion through the entire span of the aerofoil to the other marginal portion, without imparting a helicoidal warp to the aerofoil and without in any way expanding or contracting the cloth covering of the aerofoil; or when the variable camber wing is used for lateral stabilizing purposes, the curvature will be changed uniformly from one lateral portion to the central axis of the airplane.

Changes in details may be made without departing from the spirit of this invention; but,

I claim:

1. In an airplane, an aerofoil comprising an intermediate portion and front and rear marginal portions, box ribs carried by said intermediate portion in spaced relation to each other, hinges carried by said box ribs and connected to said front and rear marginal portions for hingedly connecting said

portions to the intermediate portion of the aerofoil, arms carried by said front and rear marginal portions and projecting above and below the same, and connecting wires connecting the downwardly extending arms 70 of said front and rear marginal portions to the upwardly extending arms of the opposite portions, whereby said marginal portions may be moved synchronously in the same direction, controlling means operatively connected to certain of said arms and arranged whereby said marginal portions may be synchronously operated to provide uniform curvature throughout the span of the aerofoil.

2. In an airplane, an aerofoil comprising an intermediate portion and front and rear marginal portions, box ribs carried by said intermediate portion in spaced relation to each other, hinges carried by said box ribs 85 and connected to said front and rear marginal portions for hingedly connecting said portions to the intermediate portion of the aerofoil, arms carried by said front and rear marginal portions and projecting above 90 and below the same, and connecting wires connecting the downwardly extending arms of said front and rear marginal portions to the upwardly extending arms of the opposite portions, whereby said marginal portions may be moved synchronously in the same direction, controlling means operatively connected to certain of said arms and arranged whereby said marginal portions may be synchronously operated to provide uniform curvature throughout the span 95 of the aerofoil, said marginal portions divided at the central axis of the airplane, and operating means connected to said rear portion upon each side of each division for 100 imparting curvature of different radii to the aerofoil upon opposite sides of said division.

3. In an airplane, an aerofoil, means for regulating the camber of the aerofoil for 110 varying the speed range of the airplane including a U-shaped frame, a depending saddle carried by the frame, a horizontally disposed longitudinally extending shaft rotatably carried by the saddle having oppositely threaded portions thereon, a hand wheel on said shaft, traveling nuts fitted on the oppositely threaded portions, a transversely extending centrally positioned shaft 115 rotatably carried by the frame, a drum secured to said transversely extending shaft, a hand wheel secured to said transversely extending shaft, a cable, guide pulleys for said cable carried by the nuts, said cable passing about said guide pulleys and leading 120 from each of the guide pulleys in opposite directions for connection with the aerofoil for varying the camber of the aerofoil throughout its span upon rotation of the longitudinally extending shaft, a sec- 125 130

ond cable passing about said drum and connected to the aerofoil for varying the camber of the aerofoil on each side of the longitudinal center of the aeroplane so as to present to the atmosphere different aerofoil curvatures on each side of the central axis of the aeroplane to maintain lateral sta-

bility thereof, and guide pulleys carried by said nuts and engaging the intermediate portions of said second mentioned cable on each side of said drum whereby said second mentioned cable will be actuated upon the movement of said nuts.

10
MILTON F. BABCOCK.
